WASHING MACHINE

August Guignard, Hood River, Oreg.

Application April 4, 1934, Serial No. 718,975

3 Claims. (Cl. 146—194)

My invention relates to machines for the washing of fruits, vegetables and other products.

It is particularly well adapted for the washing of products where a violent action of the treating and washing solutions is essential to thoroughly clean the material being conditioned.

My invention is particularly adapted for use where these cleaning and washing solutions are aciduous.

10 My invention is primarily comprised of a leg supported tank that is divided into compartments in which the washing solution is disposed in one of the compartments and a rinsing solution is disposed in another of the compartments.

15 A pumping impeller is disposed longitudinally of the tank. Where large quantities of material are to be treated impellers may be disposed at each side of the tank. In the smaller sizes but a single impeller may be disposed longitudinally 20 of one side of the tank.

25 Provision is made for preventing the materials being treated from being contacted with and by impeller blades. The impellers are each power driven.

20 A plurality of spaced feed rollers run longitudinally of the tank and a common drive independently drives each of the rollers. The rollers run through a bearing support disposed in the partition that separates the tank into compartments and a spiral thread outwardly extends 30 from the outer surface of the feed rollers. The rollers are power driven to thereby confine the articles being conveyed and washed between the rollers and as driven, the rollers feed the articles 35 being washed longitudinally of the tank.

A feeding station is disposed at one end of the tank and a discharge station is disposed at the oppositely disposed end of the tank.

40 Suitable means are provided for isolating the metallic parts disposed in the tank, comprising my washer, to protect the same from the disintegrating action of the acid solutions.

The primary purpose and object of my invention is to provide a relatively simple and efficient washing machine for the washing of fruit and farm products and other materials.

45 A still further object of my invention consists in so constructing the same that the metal parts comprised within the construction are protected from the disintegrating action of the acid solutions during the operation of the machine.

50 A still further object of my invention consists in so constructing the device that it will have a minimum of first cost and one that will have a

long and useful life with practical freedom from operating annoyances.

And a still further object of my invention consists in so constructing the same that it will have a maximum treating capacity commensurate 5 with the space occupied and with the power required for driving the same.

Where encrustations have formed upon the surface of the fruit that may not be easily removed in the washing operation by the ordinary 10 methods it may be found necessary to place an abrasive in the washing solution that will aid in the scouring of such coatings from the surface of the fruit. This scouring of the fruit is especially necessary where an oil spray is used in the 15 orchards. In the washing of some of the varieties of fruit the wax coat that forms upon the fruit in the late season has a tendency to encompass the spray residue as the arsenate of lead residue and it is difficult to remove the spray 20 residue by the ordinary processes now in general use. Under such conditions I place an abrasive in the treating tanks and especially in the primary washing tank. The abrasive, or scouring material should be light in weight and one 25 that will not easily disintegrate through the violent action imparted to the treating solutions by my impellers. I have had splendid results in the use of saw dust. I have tried cork particles and have also had satisfactory results from its 30 use. I do not wish to be limited in the use of saw dust and cork as other materials may be used to produce equally satisfactory results. The materials that are to be used as the abrasive should be such that it may be confined within the 35 treating tanks and one that will not form encrustations upon the machine parts and upon the walls of the tanks. It should also be of such a nature that it may be passed through the pump cylinders and the passageways that lead to and 40 away from the pump cylinders when such pumps are used in the washing operations. It is desirable to use an abrasive, or scouring material that will not harden when placed in the washing solution. It is equally important to use a material that will not penetrate, or break the skin 45 of the fruit. I believe that best results are to be obtained where the scouring materials will float upon the surface of the solutions when the solutions are in a quiescent state. Relatively coarse and uniform sawdust from the soft woods are believed to produce the best results and this is especially true when certain varieties of pears 50 are to be washed.

45

50

55

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

- 10 Fig. 1 is a side view of the machine.
- Fig. 2 is a sectional side view of the machine.
- Fig. 3 is a top plan view of the machine.
- Fig. 4 is an end view of the machine. This view is an end view of the drive end of the machine.
- 15 Fig. 5 is a sectional end view of the machine. This view is taken on line 5—5 of Fig. 1, looking in the direction indicated.

- Fig. 6 is a perspective end view of one of the impellers shown removed from the machine.
- 20 Fig. 7 is a plan view, partially in section of the impeller shaft shown removed from the impeller assembly.

- Fig. 8 is a sectional end view of the impeller shaft. This view is taken on line 8—8 of Fig. 7, 25 looking in the direction indicated.

- Fig. 9 is a fragmentary top plan view of the impeller shaft and of the journal bearing illustrating the shaft having the journal bearing removed therefrom.

- 30 Fig. 10 is a fragmentary plan view, partially in section of the feed rollers and the connections that secure the same together in the respective and adjacent treating tanks.

- Fig. 11 is a fragmentary sectional side view of 35 the tank disposed adjacent the end of the impeller and is made to illustrate a deflector plate that is disposed adjacent the end of the impeller. This view is taken on line 11—11 of Fig. 3, looking in the direction indicated.

- 40 Fig. 12 is a side view of the deflector illustrated in Fig. 11.

Like reference characters refer to like parts throughout the several views.

- I preferably form my device of a fabricated 45 frame that is supported upon and within suitable supporting posts 1. A treating tank or vat 2 is disposed within the frame. This tank is partitioned into primary and secondary treating tanks.

- 50 Since an aciduous solution may be used in the treating of the fruits or vegetables it is necessary to so construct the assembly that the acids will not disintegrate the metals used in the construction of the device.

- 55 The treating solution tank is comprised of a plurality of bottom members 3 and side members 4. The bottom and side members are preferably made of wood and are secured together by longitudinal strips 5 that are placed within matched 60 grooves that are formed within the adjacent edges of the side and bottom members.

- A top or cover 6, preferably made of sections is 65 removably placed upon the top of the side members to form an enclosed treating solution holding tank or vat.

- A power driven impeller runs longitudinally of 70 one side of the tank. To render the impeller effective, the same runs and operates within a half circular shell. This half circular shell is comprised of a bottom member 7 and a top member 8. The same are secured together at their adjacent edges 9 and 10 to form a shell that forms a segmental arc 11 that runs longitudinally of the top and bottom member and the segmental arc 75 forms substantially a half circle.

The splitting of the half circular shell makes it possible to adjust the shell as shrink or swell occurs in the split members and/or in the impeller blades. This adjustment makes it possible to maintain a proper working relationship between the impeller and the housing therefor.

The impeller is comprised of a shaft 12, and blades, here shown as four in number, at 13, 14, 15 and 16. Each of these blades is attached to the shaft and to each other. A power take-off 10 is provided at one end of the impeller shaft and a sprocket 17 is disposed upon the shaft and to which, and about which a driving chain 18 is trained for supplying the power of rotation to the shaft.

The impeller shaft is journaled relative to the frame in suitable journal bearings 19, 20 and 21. A stub shaft 22 is journaled at the drive end of the frame in bearings 23 and 24 and power rotation is applied to the shaft 22 by any suitable 20 means as by the placing of a pulley 25 thereupon and to which any suitable belt may be attached. The power for the machine is secured from any suitable source, not here shown.

A sprocket 26 is placed upon the shaft and the 25 chain 18 is trained about the respective sprockets 17 and 26. The central portion of the impeller shaft 12 is made square and the ends of the shaft, as shown at 27 and 28, are made cylindrical to adapt the same to the respective journal bearings. 30 The blades of the impellers are preferably made of suitable wood and that portion of the shaft that is disposed within the tank or vat is treated with a non-porous material, as asphaltum, or tar in advance of the impeller blades being attached 35 thereto to render the same impervious to the disintegration of the acid treating solutions.

In order that the impeller blade members may be properly reinforced, reinforcing bars 29 and 30 are placed upon the oppositely disposed sides of 40 the companion members, and suitable fastening bolts pass through the reinforcing bars and through the impeller blade members 14 and 16 and 13 and 15 and through the shaft. The peripheral edge of each of the blades is chamfered 45 and runs in juxtaposition with the inner surface of the top and bottom members that form the half circular shield.

The fluid picked up by the blades is trapped and is carried between the inner surface of the 50 half circular shield and the impeller blades. The power rotation of the impeller blades thus forms a pump that throws the treating fluids in a sheet and with great agitation over the top surface of the materials being treated that are carried 55 through the treating tank or vat.

Shields 31 and 32 are placed at the oppositely disposed ends of the impeller, and the ends of the impeller blades operate in close working relationship with the inside surfaces of the shields 60 31 and 32.

In order that the current of pumped fluid being delivered from the impeller blades may be delivered in a sheet of lesser width than that of the length of the impeller blades, I place blocks 65 33 and 34 upon the inner surface of each of the shields. This is shown somewhat in detail in Figs. 11 and 12. The inner surface of these blocks is curved as illustrated at 35 in Figs. 11 and 12 and this confines the pumped fluid and 70 delivers the same within the tank without end splash being developed outside of the length of the impeller blades.

These shields also force the stream of fluid being pumped toward each other from the ends 75

of the impeller toward the center of the impellers. This further increases the agitation of the pumped washing fluid to thereby increase the washing and scrubbing efficiency of the washing solutions.

A screen 36 preferably made of a fabric material as canvas is disposed transversely of the initial treating tank and it is disposed immediately at the rear of the shield 32. The screen is 10 slotted as illustrated at 37 in Fig. 5 to form downwardly extending fingers 38 beneath which the materials being conveyed through the treating vat are made to pass. The screen prevents splash from the primary treating tank into the 15 secondary rinsing tank and at the same time permits a free flowing of the materials being washed past the screen without any resistance. A feeding station 39 is provided at the entrance end of the machine and materials, from a source 20 of supply not here shown, are fed down the chute 40 into the feeding station.

A plurality of feeding rollers 41 extend longitudinally of the primary washing tank and of the secondary rinsing tank. These feeding rollers 25 are parallelly disposed relative to each other. A screw thread is spirally disposed upon the outer surface of each of the feeding rollers.

I have found satisfactory results may be obtained in the placing of this spiral thread about 30 the feed roller by placing a strand of rope there-around of the required size. The power driven rollers are so spaced that the articles being washed will not pass therebetween. The drive for these spaced rollers is accomplished by the 35 placing of a pair of coating gears 42 and 43 upon the respective shafts 22 and 44. The gear 43 being disposed upon the driving stub shaft 22 and the gear 42 being placed upon the driven shaft 44. Driving sprockets 45 and 46 are disposed upon the shaft 44 and driving and idler sprockets are disposed about each of the shafts upon which the feed rollers are mounted, and driving chains 47 and 48 are trained about the respective driving and idler sprockets and about 40 the sprockets disposed upon the shaft 44. This driving assembly is best illustrated in Fig. 4.

I provide a separator bar 49 longitudinally of the primary and the secondary treating tanks. The upper end 50 of the separator bar inwardly 45 extends and forms a lip 51 that extends toward and terminates above the feed rollers 52. The purpose of this separator bar is to prevent the materials being washed from coming in contact with the impeller and to confine the flow of the material within the respective tanks. The spacing of the separator bar from the adjacent feed roller 52 is sufficient to prevent articles being washed from falling therebetween.

A bar 53 is also placed adjacent the outside 50 feed roller 54 and prevents the articles being washed from being carried between the feed roller 54 and the inside wall 55 of the tank.

The primary treating tank and the secondary treating tank are separated by a division wall 56 and the shafts upon which the respective feed rollers are mounted pass through this division wall and the bearings disposed about the shaft, where they pass through the wall, are made sufficiently tight to prevent the flowing of the 65 aciduous treating solutions from the primary treating tank into the secondary tank into which the rinsing solutions are maintained.

The feed rollers in the secondary washing tank are a continuation and are made similar to those 70 of the feed rollers within the primary treating

tank. The discharge end wall 57 of the secondary treating tank is made sufficiently low to permit the articles to be delivered over the top of the same by the feed rollers. These washed and rinsed articles are delivered onto an inclined 5 discharge platform 58 and from where the conditioned articles are delivered to sorting and inspection tables.

A bearing forming member 59 is superposed the division wall 56 and a journal bearing 60 is 10 provided therein for each of the rollers. Each of the roller members has connecting bars 61 and 62 disposed therein and each of the connection bars is secured to the rollers by suitable fastening pins 63 and 64. The bearing member 61 15 has a squared hole 65 disposed within its end and the outer surface of the member 61 is made to work in connection with the journal bearing 60. A projection 66 is disposed upon the end of the connection 62 and the same is also made square 20 and is fitted into the squared socket disposed within the member 61. This makes these rollers, though of separate parts, into a continuous member and about which a spiral thread is disposed which feeds the particles being conditioned longitudinally of the treating tank.

After the assembly has been made the metal is isolated through the use of tar, bitumin or other suitable acid insulating agencies to prevent the direct action of the aciduous solution upon the 30 respective metal materials disposed within the bearings and disposed within the rollers. The squared portion of the shaft 12 is insulated from the aciduous solutions by pitch or bitumin material as heretofore described.

Rubber sleeves 67 and 68 are disposed adjacent the squared portion of the shaft 12 as illustrated in Fig. 7 and these rubber sleeve members pass through the walls 69 and 56 and the shields 31 and 32 respectively and through which sleeves 40 the shaft passes in emerging from the treating solution tank. The flanges 71 and 72 are formed integral with the sleeve and form a connection between the sleeve and the inner wall of the tank. The rubber sleeves have outwardly extending ends 45 as illustrated at 73 and 74 to form a connection adjacent the outer surface of the respective flange members and about shafts 27 and 28 respectively where they pass through the tank walls. This sleeve protects the metal shaft between the ends 50 of the impeller and the inner side walls of the tank; this is best illustrated in Fig. 3 at 75 and 76.

While the form of mechanism herein shown and described is admirably adapted to fulfill the 55 objects primarily stated, it is to be understood that it is not intended to confine the invention to the embodiment herein shown and described, as it is susceptible of embodiment in various forms, all coming within the scope of the claims 60 which follow.

What I claim is:

1. In a device of the class described, the combination of a shaft, a portion of the shaft between its ends being rectangular in cross sectional 65 area, impeller blades secured to the rectangular portion of the shaft and a cementitious material insulating the rectangular portion of the shaft from liquid penetration, the remaining portion of the shaft from the rectangular portion to each 70 end being cylindrical, rubber sleeves disposed about a portion of each cylindrical end section and flanges secured to the rubber sleeves and disposed adjacent the outer ends of each of the rubber sleeves.

2. In a device of the class described, the combination of a shaft having an impeller disposed upon the central portion of the shaft, means for insulating that portion of the shaft upon which the impeller is disposed from water contact, rubber sleeves abutting the impeller ends and extending toward the ends of the shaft, rubber flanges disposed about the rubber sleeves and disposed adjacent the outer ends of the sleeves and means for confining the splash developed by the impeller within the length of the impeller blades.
3. In a washing machine having a fluid therein, the combination of a shaft having an impeller disposed upon the central portion thereof, said end portions of the shaft being cylindrical and passing through the end walls of the washer, rub-

ber sleeves disposed about the cylindrical ends of the shaft between the end of the impeller and the end walls, rubber washers disposed about the rubber sleeves and adjacent the end walls, means disposed at each end of the impeller for confining the splash developed by the impeller within the length of the impeller blades, splash guides adjustably secured to the side wall of the washer adjacent the impeller, said guides having a substantially quarter circle face spaced apart from the longitudinal outer edges of the impeller blades, and means for vertically adjusting the splash guides for determining the volume and distance of the splash.

AUGUST GUIGNARD.
